CARRYING AND DISPLAYING DEVICE FOR
PHOTOGRAPHS OR THE LIKE

George J. Soldati, New York, N. Y.

Application March 19, 1942, Serial No. 435,430

1 Claim. (Cl. 40—82)

The invention relates to a novel and improved device for carrying and displaying photographs and the like, and the primary object of the invention is to provide a simple, efficient and practical device of this character in "fountain pen" form which is especially adapted to carrying by men in the service and other persons.

Other important objects and advantages of the invention will be apparent from a reading of the following description taken in connection with the appended drawings, wherein for purposes of illustration a preferred embodiment of the invention is shown.

In the drawings:

Figure 1 is a general side elevational view showing the picture ribbon extended and the suspension ring engaged over a nail or other wall hanging means.

Figure 2 is an opposite side elevational view showing the ribbon in retracted position in which the device is carried after the manner of a fountain pen.

Figure 3 is a vertical longitudinal sectional view.

Figure 4 is an enlarged transverse vertical sectional view taken through Figure 2 along the line 4—4 and looking toward the direction of the arrows.

Figure 5 is an enlarged inner end elevational view of the removable and rotatable plug.

Figure 6 is a longitudinally contracted view of the roller.

Referring in detail to the drawings, the numeral 5 generally designates the combination carrying and displaying device, the same consisting of a cylindrical tube 6 of any suitable material or non-metallic in character which has plugged in one end thereof the stationary cylindrical plug 7 which has the reduced portion fastened telescopically in the end of the cylinder. A fountain pen type of pocket clip 9 occupies the usual position on the exterior of the cylinder 6 and is mounted thereon by means of a ring 10 circumscribed on the reduced portion of the plug 7 and between the end of the cylinder 6 and the larger diameter portion of the plug as clearly illustrated in Figure 3 of the drawings. Axially arranged on the inner end of the plug 7 is a circular series of equally circumferentially spaced laterally expansible pins or spring fingers 11 which are conformably curved to grip the outside of a spherical head 12 on the rotatable rod 13 which is socketed in a rotatable and removable plug 14 which has a reduced portion 15 rotatably engaging in the end of the tube 6 opposite the plug 7. The grip of the curved fingers 11 on the sphere 12 is such as to prevent relative longitudinal movement of the rod or shaft 13 while

allowing axial rotation thereof. The plug 14 and shaft 13 are readily removed by exerting sufficient force in a direction away from the fingers 11 and restored to operative position by forcing the sphere in between the fingers.

Rolls on the rod 13 and secured thereto against rotation relative thereto is a ribbon 16 of flexible fabricated or other suitable material, the outer end or edge of which is provided with the rigid finishing piece 17 which itself is provided with an eye 18 loosely securing a hanging ring 19. The finishing piece is wide enough to go easily into a longitudinal slot 21 formed in the side of the cylindrical tube 6, the finishing piece being provided on opposite sides with longitudinal projections 20 to prevent the finishing piece from entering the slot 21 too far.

The picture or photograph or other representation is secured to or otherwise applied to or manufactured in the ribbon 16 as indicated in Figure 1 of the drawings, so that they may be displayed by pulling out the ribbon. The device may be hung upon a wall nail or other hanging means 22 as indicated in Figure 1 of the drawings when desired. To attract the ribbon and its picture from the display position indicated in Figure 1 of the drawings, the rotatable knob 14 is rotated in a direction to roll the ribbon on to the shaft 13 and bring the finishing piece 17 into the slot 21.

Although I have shown and described herein a preferred embodiment of the invention, it is to be understood that the application of the invention is not confined thereto, except as defined by the subjoined claim.

Having described the invention, what is claimed as new is:

In a device of the class described, a tubular casing resembling a fountain pen barrel and having a longitudinal slot in one side thereof, a plug rotatably fitted in one end of the casing, a second plug fixed in the other end of the casing, a shaft fixed at one end in the rotatable plug for rotation in the casing by said rotatable plug and having the opposite end thereof contiguous with the fixed plug for attachment thereto against endwise movement of the shaft out of the casing, a flexible ribbon wound on the shaft for unwinding therefrom by rotation thereof in one direction and for extension through said slot, and means to detachably attach said opposite end of the shaft to said fixed plug and for rotation relative thereto comprising a spherical head on said opposite end of said shaft, and a circular series of curved spring fingers extended from the fixed plug for snap action frictional engagement with said head.

GEORGE J. SOLDATI.
